Primary Examiner — Cynthia Ramirez*(74) Attorney, Agent, or Firm* — Workman Nydegger**CLAIM**

The ornamental design for a conveyor belt module, as shown and described.

DESCRIPTION

FIG. 1 is a top perspective view of a conveyor belt module according to the present invention.

FIG. 2 is a bottom perspective view of the conveyor belt module of FIG. 1.

FIG. 3 is a bottom view of the conveyor belt module of FIG. 1; and,

FIG. 4 is an end view of the conveyor belt module of FIG. 1.

The broken lines in the figures are to show portions of the conveyor belt module which are not part of the claimed design.
